CANISTER WALL SHELF UNIT

Filed May 10, 1952

FIG. 1

FIG. 2

INVENTOR:

Collier L. Curry

UNITED STATES PATENT OFFICE

167,972

CANISTER WALL SHELF UNIT

Cullen L. Curry, Mobile, Ala.

Application May 10, 1952, Serial No. 19,681

Term of patent 14 years

(Cl. D33—3)

To all whom it may concern:

Be it known that I, Cullen L. Curry, a citizen of the United States, residing at 1717 Magpie Street, in the city of Mobile, county of Mobile, and State of Alabama, have invented a new, original, and ornamental Design for a Canister Wall Shelf Unit, of which the following is a specification, reference being made to the accompanying drawing, forming a part thereof.

Fig. 1 is a top plan view of a canister wall shelf unit showing my new design.

Fig. 2 is a side elevational view thereof.

Fig. 3 is a front elevational view thereof.

I claim:

The ornamental design for a canister wall shelf unit, as shown.

CULLEN L. CURRY.
